US00D908007S

(12) **United States Design Patent** (10) **Patent No.:** **US D908,007 S**
(45) **Date of Patent:** **** Jan. 19, 2021**

(54) **GAP FILLING PACKAGING ELEMENT**

(71) Applicant: **Rational Packaging LLC**, Springfield, TN (US)

(72) Inventor: **Samuel C. Voorhees**, Louisville, KY (US)

(73) Assignee: **Rational Packaging LLC**, Springfield, TN (US)

(**) Term: **15 Years**

(21) Appl. No.: **29/710,274**

(22) Filed: **Oct. 22, 2019**

Related U.S. Application Data

(63) Continuation-in-part of application No. 29/667,164, filed on Oct. 18, 2018, which is a continuation-in-part of application No. 29/593,144, filed on Feb. 6, 2017, now Pat. No. Des. 871,213, and a continuation-in-part of application No. 29/593,147, filed on Feb. 6, 2017, now Pat. No. Des. 871,908.

CLAIM

The ornamental design for a gap filling packaging element, as shown and described.

DESCRIPTION

FIG. 1 is an upper, right, perspective view of a gap filling packaging element, showing my new design;
FIG. 2 is a lower, left perspective view thereof;
FIG. 3 is an upper, rear perspective view thereof;
FIG. 4 is a lower, rear perspective view thereof;
FIG. 5 is a top view thereof;
FIG. 6 is a bottom view thereof;
FIG. 7 is a left side view thereof;
FIG. 8 is a right side view thereof;
FIG. 9 is a front view thereof; and,
FIG. 10 is a rear view thereof.
